UNITED STATES PATENT OFFICE.

EDGAR I. PROUTY, OF ALBANY, OREGON.

TROUSERS-HANGER.

1,102,545.

Specification of Letters Patent.

Patented July 7, 1914.

Application filed January 5, 1912. Serial No. 669,522.

To all whom it may concern:

Be it known that I, EDGAR I. PROUTY, a citizen of the United States, and a resident of Albany, in the county of Linn and State of Oregon, have invented certain new and useful Improvements in Trouser-Hangers, of which the following is a specification, reference being had to the accompanying drawings.

10 This invention has relation to certain new and useful improvements in hangers especially adapted to be used in holding trousers in a suspended condition; and the object of my invention is to provide a hanger of this 15 general character made of a single length of spring wire, including two spring pressed arms each carrying a flat wooden strip serving as a jaw and adapted to receive suitable advertising matter.

20 Another object is to provide a trouser hanger of neat and inexpensive nature and of compact and durable construction, which shall be capable of convenient adjustment upon a hook or nail to removably receive the 25 flat folded leg ends of a pair of trousers to hold the same in neat readily accessible suspended condition.

With these and other objects in view the present invention consists in the combination and arrangement of parts as will be hereinafter more fully described and finally pointed out in the appended claim, it being further understood that changes in the specific structure shown and described may be 35 made within the scope of the claim, without departing from the spirit of the invention.

In the accompanying drawings forming a part of this specification and in which like numerals of reference indicate similar parts 40 in the several views: Figure 1 is a perspective view of a trouser hanger, embodying my invention. Fig. 2 is a section on line 2, 2 of Fig. 1.

In my present invention, I aim to provide 45 a trouser hanger having two non-rusting jaws between which the folded ends of the trouser legs are firmly clasped so that the garment may be held in a suspended condition.

50 In carrying out the object of my invention, I employ a carrying member made of spring metal wire which is tinned or galvanized to prevent rusting of the same. In the drawing the numeral 1 represents a spring 55 coil from which extend in spaced relation the two resilient stems, 2, 2. Each stem is

continued in an obliquely extending crooked arm, the upper portion of each arm being marked 3, while the lower portion of each arm is marked 4. As shown the arm portions 3 extend oblique to the stems and pass one another and are held in juxtaposition. The lower ends 4 of the crooked arms are held in parallel spaced relation. Each crooked arm ends in an oblong square spring 60 loop 5, said loops extending at right angles to the stems 2. As shown in Fig. 1, each loop terminates in a counterpart crooked arm 6, ending in a securing coil 7 wound about the base of its connected stem 2 so that 65 each loop 5 is connected to its stem by a crooked arm of double thickness. The loops 5 are of a length so that they will slightly extend over the ends of the trouser legs when clamped upon the garment. While 70 the hanger is made of galvanized, tinned or plated material, in order to guard against rusting of the garments when they are suspended in a moist or damp condition, I provide the loops 5 with wooden jaws 9. As 75 shown in Fig. 2, each jaw 9 has a skirting rabbet 8, and sprung into the rabbet are the loops 5. In order to further hold the wooden or other non-rusting jaws 9 to the loops, I employ the staples 11. These jaws 80 perform a double function in that they are adapted to receive suitable advertising matter.

These trouser hangers can be very cheaply made, so that they can be given away by 85 tailors and others, in doing which the advertiser prints or impresses suitable advertising matter upon the outer faces of the wooden jaws.

While the trouser hanger may be suspended by means of the spring 1, I still provide the same with a hook 12 the lower end 90 of which I coil about the spring in the manner shown in the drawings.

The hanger is simple and inexpensive in 95 construction and both durable and efficient in operation, and the device may be adjusted upon a garment with ease, accuracy and despatch.

Having thus described my said invention, 100 what I claim as new and desire to secure by United States Letters Patent is:

A device of the character described, comprising a member made of a single length of spring wire bent midlength to form a spring 110 coil from which extend in spaced relation two resilient stems each being continued in

an obliquely extending crooked arm said crooked arms passing one another and held in juxtaposition, the lower ends of said crooked arms being normally held in parallel relation, each crooked arm ending in an oblong spring loop said loops extending at right angles to said stems each loop terminating in a counter-part crooked arm ending in a securing coil wound about the base 10 of its connected stem, so that each loop is connected to its stem by a crooked arm of

double thickness, in combination with two wooden jaws each having a skirting rabbet into which said loops are sprung, and means to hold said loops to said jaws.

15

In testimony whereof I affix my signature, in presence of two witnesses.

EDGAR I. PROUTY.
